UNITED STATES PATENT OFFICE

MICHAEL J. GRACE, OF CHARLESTON, SOUTH CAROLINA, ASSIGNOR, BY MESNE ASSIGNMENTS, TO THE GAMEWELL COMPANY, OF NEWTON UPPER FALLS, MASSACHUSETTS, A CORPORATION OF MASSACHUSETTS

KEY AND LEVER GUARD FOR FIRE-ALARM BOXES

Application filed June 30, 1924, Serial No. 723,418. Renewed March 30, 1929.

The present invention is a guard for keys or pull levers of fire alarm signal boxes. This invention is an improvement over the well known Cole key guard shown and described in United States Patent No. 824,411, wherein a transparent plate is mounted in a spring operated door, the door being arranged before the key or alarm pull lever. In this type of device it is necessary to first break the glass or frangible element which releases the spring door and permits the same to swing open giving ready access to the key or pull lever. This type of device is objectionable because it is found that in a number of instances the person sending the alarm breaks the glass with his hand and the shattered glass cuts or otherwise injures the hand of the person. Furthermore it is necessary with devices of the type of the Cole device to replace the glass after each alarm.

It is also well known that it has been proposed to have a non-frangible, transparent element covering the key or pull lever. But in these cases the door supporting said element must be manually and deliberately opened before access is gained to the pull lever or the key. In this instance the well established practice of breaking the glass to gain access to the key or pull lever, with which practice all persons are fully familiar, has been departed from which may cause confusion in the sending of the alarm, resulting in no alarm being sent in,—by reason of the fact that the door of the guard having been deliberately pulled or otherwise opened a person may assume that the alarm has been sent in and neglect to turn the key or pull the alarm lever.

The present invention has for its object to overcome all of the above stated drawbacks and to provide further an economical and efficient key or lever guard adhering to the well known practice and instructions which have long appeared on all alarm boxes, to first break the glass and to turn key or pull lever.

The invention further has for its object the elimination of the usual key lock for maintaining the guard door closed and the provision of a door which will snap into place and which will be readily tripped open upon

the striking of the door or glass with the knuckles or other instruments without breaking the glass. The glass is made sufficiently thick or otherwise constructed to withstand an ordinary blow from the hand without breaking it. However it may be broken, if found necessary, with a suitable instrument thereby under any condition assuring access to the key or lever.

The invention further resides in the sundry details of construction, combination and arrangement of parts which are shown in the accompanying drawings and described in this specification.

In this specification and the annexed drawings, the invention is disclosed in the form in which it is considered to be the best, but the invention is not limited to such form because it is capable of being embodied in other forms; and it is to be understood that in and by the claims following the description herein it is intended to cover the invention in whatever form it may embody within the scope thereof.

In the drawings in which the preferred embodiment of the invention is shown, as at present devised:

Figure 1 is a front view of a signal box provided with a key or lever guard attachment constructed in accordance with the invention;

Fig. 2 is a vertical sectional view taken substantially on line 2—2 of Fig. 1;

Fig. 3 is a modified form of the lock and trip lever; and

Fig. 4 is a modified structure embodying the fundamental features and principles of the invention.

Referring particularly to the details of the drawings, 1 indicates the shell or housing of the usual fire alarm box which may be provided with a movable front face or door 2, in which there is a slot through which a suitable pull lever is extended to be accessible for sending the alarm or in which may be provided a key lock accessible to the sender of the alarm in a manner which is well understood in the art. This pull lever 3 or key, as the case may be, is enclosed by the usual guard housing 4 equipped with a spring

actuated hinged door 5 of substantially the same structure now commonly in use. It may be found desirable however, to eliminate the projecting guard housing 4 and to provide a suitable depression or recess in the door 2 of the box. However such depression or recess will be equipped with the spring actuated door 5, preferably of the swinging type hinged at its lower edge as at 6 and being moved to open position in any suitable manner by a spring or other means 7.

The present invention deals more particularly with a means for maintaining the door in its normal closed position, shown in Figs. 1, 2, and 4, but which will be actuated when pressure is exerted on the door or frangible panel 8 to release the door from its normally closed latched position and to permit the spring means 7 to open the door as soon as the pressure of the blow has been released.

As previously stated it is the purpose of this invention for the sender of the alarm to practice the time-honored method familiar to all persons by first breaking the glass on the door 5. But since it is the practice of most people to attempt to break the glass with their hand, it is the aim of this invention for the door to be released when the glass of the door is struck by a blow from the hand but without actually breaking the glass. To this end the glass is made of greater thickness than usual or of such construction as to withstand an ordinary blow from the hand without breaking, but which may be broken, if found necessary, with a suitable instrument thereby under all conditions assuring access to the key or lever.

One means for latching the door 5 in its normally closed position is shown in Figs. 1, 2, and 3 and consists of a lever 9, substantially of the bell-crank type pivotally mounted at its angular portion in a bracket or projection 10 extending laterally from the inner face of the door 5 at or adjacent the distal edge thereof, or at any other suitable portion which may be found more convenient and desirable on the door 5. The lever 9 is so designed and constructed as to have the extremity A of one arm thereof to engage against the usual glass panel 8, in the manner clearly shown in Figs. 1 and 2, and the end B of the other arm thereof designed to act as a detent to engage with and abut an edge of the door opening in the housing 4, as clearly shown in Fig. 2.

The frangible panel 8 is, preferably, fitted in rabbets in the door 5 and is normally held tightly in the rabbets by the extension D of the spring 7. The manner of mounting the panel 8 may be varied in any suitable or desired way which will permit the panel to move, under pressure, inwardly relative to the door 5, as indicated in dotted lines, Fig. 2. The latch lever 9 is normally urged to its full line position shown in Fig. 2 by a light spring

11 connected with one arm of the lever and with the bracket 10. However it may be found desirable in some instances to substitute a counter-balance on the lever for the spring 11. The door actuating means 7 may be any suitable means, but for the purpose of the present showing consists of a flat spring having one end secured to the frame of the door 5, as in F, and one end E under tension engaging against the inner wall of the bottom of the guard housing 4.

From the above it will be seen that when a person is about to turn in an alarm, in the event of fire, he will proceed as is usual to give the frangible panel 8 a blow, in an attempt to break the panel and gain access to alarm pull-lever or key. If this blow is delivered by the hand, the panel will be sufficiently strong to resist breaking, but will move inwardly, as indicated in dotted lines, Fig. 2, under the blow, moving the end A of the lever 9 inwardly with it, which in turn causes the end B of the lever to move out of the path of the keeper edge 12 of the guard box; and since the spring 7 is constantly exerting its pressure on the frame of the guard box door 5, the door will be moved slightly outwardly, as indicated in dotted lines Fig. 2, to clear the end B of the latch lever 9 from the keeper 12, and as soon as the pressure from the blow is relieved from the panel 8, the spring 7 will complete its swinging movement of the door, and move it to the full open position, shown in dotted lines of Fig. 2. This operation renders ready access to the usual alarm pull-lever or to the lock-key of the door 2 of the alarm box, according to the type of box upon which the invention is installed. The panel 8 will be immediately returned to its position in the rabbet, as soon as the pressure of the blow is relieved therefrom, by the spring 11, by reason of the end A of the lever 9 being in contact with the panel. After the alarm has been given, the proper authorities can again close the door 5 of the guard housing by merely moving the door closed and the end B of the lever 9 will snap into latched position with the keeper edge 12. It will thus be seen that when the alarm is thus given it will not be necessary to replace the frangible panel 8, because the same is not broken, and the hand of the sender of the alarm is in no way injured or jeopardized by the breaking of the glass. In the event, however, it becomes necessary to break the panel 8, or if the sender of the alarm uses an instrument to break the panel, the same may be readily broken and under ordinary conditions the impact will be sufficient to

cause an inward swing of the end A of lever 9 to release the latch B and permit the door to swing open; but if for any reason the latch does not open, access can be had through the broken pane or panel to the pull lever or

key, thus rendering the device fool-proof. A new frangible panel 8 may be readily inserted in the rabbet behind the spring D and the arm A of the lever 9, if required.

In Figure 3 a modification of the lever 9 is shown, in the form of the lever 9^a provided with a double or yoke-like arm instead of the single arm A. This yoke arm A' is designed to have its extremities lie on each side of a panel and engage therewith so as to eliminate any possibility of the panel twisting under the impact of a blow without transmitting the inward movement of the panel to the lever.

A further modification of the invention is shown in Fig. 4 wherein the door to the key or lever guard 4, has the latch means operated by the inward movement of the door 5^a instead of by the inward movement of the glass panel only. In this form of the invention the frangible panel 8^a may be rigidly mounted in the door, but subject to renewal in the usual manner if broken, and any impact received on the panel 8^a or on the frame of the door will cause the door 5^a to move inwardly for a slight distance. This movement of the door causes the detent 15 to ride on the bevel surface of the keeper 16 and thereby be depressed a distance to permit the spring 30 pressed pawl 17 to engage in the notch 18, thus releasing the door from closed position and permitting a suitable actuating means, such as shown at 7 in Fig. 2, to move the door to open position as soon as the pressure of 35 the impact has been moved from the door 5^a or the panel 8^a. After the alarm has been given the detent 16 may be released from ineffective position by withdrawing the pawl 17 and the door swung back and snapped to latch position. It will be noted that the forward edge of the keeper is cut away at 19 to prevent the detent from being depressed sufficiently, while the door is being closed, to permit the pawl 17 to engage in the notch 18. In this form of the invention as in the form shown in Figs. 1 to 3 inclusive, the frangible panel will be of sufficient thickness to withstand the ordinary blow of the hand, but it may be broken when necessity requires.

It will be manifest that should the guard door 5 or 5^a become accidentally open it may be snapped in close position by any person.

What I claim is:

1. A key or lever guard for fire alarm boxes including a movable cover member to be positioned before said key or lever and normally biased to move to opened position, means for holding said cover in closed position before said key or lever and for releasing said cover upon pressure against a portion of the cover in a direction opposite to the normal opening movement of the cover.

2. A guard consisting of a movable cover member to be arranged before a key or lever of a fire alarm box, means normally tending

to move said cover to open position to uncover said key or lever, and means for maintaining said cover outwardly in closed position and operable for releasing said cover when an exterior pressure is exerted against a portion of said cover in a direction opposite the normal opening movement of the cover. 70

3. A guard to be arranged before a key or lever of a fire alarm box and including a door having a transparent portion therein to expose said key or lever and tending to move normally to open position, means for holding the door in closed position before said key or lever, said holding means including mechanism for actuating the same to release the door, when external pressure is exerted against a portion thereof to move said portion slightly in a direction opposite to the opening movement of the door, whereby the door is allowed to move to open position to expose said key or lever when said pressure is removed. 75

4. A guard to be arranged before a key or lever of a fire alarm box and including a door having a transparent portion therein to expose said key or lever, and tending to move normally to open position, means for holding the door in closed position before said key or lever, said holding means including mechanism for actuating the same to release the door, when external pressure is exerted against the transparent portion thereof, and allow the door to move to open position to expose said key or lever, said transparent portion of the door consisting of a frangible element adapted to be broken by an unusual pressure or blow exerted against the transparent portion. 90

5. A guard for the key or pull lever of fire alarm boxes consisting of a door pivotally mounted at its lower end and to be disposed before said key or lever, means for maintaining said door in said last mentioned position and for releasing the door when external pressure or a blow is exerted thereagainst, means for swinging said door open on its pivot when so released, and a movable frangible element in said door adapted to withstand ordinary pressure or a blow from the hand and operatively associated with said door releasing means, whereby the latter may be actuated. 105

6. A guard for a key or pull lever of fire alarm boxes comprising a door like element consisting of a frame mounted to be moved to closed position before said key or lever, a transparent element adapted to withstand ordinary blows from the hand and mounted in said frame to have a relative movement thereto under external pressure or a blow thereagainst, means for maintaining said door in normally closed position before said key or lever and actuated by said relative 120

125

130

movement of said transparent element for releasing said door.

7. A guard for a key or pull lever of signal boxes including a door to be positioned before said key or lever and normally biased to move to open position, said door including a frame and a frangible panel mounted in the frame and of such character as to withstand pressure or an ordinary blow from the hand, 10 said panel having a yieldingly inward movement relative to the frame under said pressure or blow, a latch means on the frame for normally holding said door in closed position and arranged relative to said panel to be 15 actuated by the inward movement of the latter to release said door.

8. In an attachment for signal boxes, an inclosure including a door-like member pivoted at its lower edge, means normally urging 20 said door to open position, a frangible transparent panel in said door of such character as to withstand pressure or a blow, from the hand, spring means for maintaining said panel in position in the door and yieldable 25 under said pressure or blow to permit said panel to have an inward movement relative to the door, a latch means normally maintaining the door in closed position, a portion of said latch means being arranged relative 30 to said panel to be engaged by the latter when moved inwardly relative to the door, whereby the latch means is actuated to release the door.

9. A guard attachment for signal boxes, a 35 door pivotally mounted at its lower edge, a frangible transparent panel mounted in said door of such character as to withstand pressure or a blow, from the hand, a spring secured to the door and having one portion engaging a stationary member and an opposite portion engaging said panel, whereby the door is normally urged to swing open and said panel is yieldingly maintained in the door, and a latch means normally maintaining 40 said door in closed position and having a part thereof positioned to be engaged by said panel when moved inwardly under pressure or a blow, whereby said latch means is actuated to release said door.

10. A guard attachment for signal boxes, a door pivotally mounted at its lower edge, a frangible transparent panel of such character as to withstand pressure or a blow, from the hand, mounted in said door to move inwardly under said pressure or blow relative to the door, means normally urging said door to open position, an inwardly extending bracket on said door, a pivoted latch member 55 on the bracket and having two angular arms extending outwardly toward the door, one of said arms being positioned to engage with the edge of the door opening for maintaining the door in closed position to engage with 60 said panel, whereby the latch member is ren-

dered ineffective when the panel is moved inwardly, and means for normally urging said latch member to effective position.

In testimony whereof I have hereunto set my hand.

MICHAEL J. GRACE.
